US0D1081392S

(12) United States Design Patent (10) Patent No.: US D1,081,392 S
(45) Date of Patent: * Jul. 1, 2025

(54) BAG FOR FOOD PACKING

(71) Applicant: CJ CHEILJEDANG CORPORATION, Seoul (KR)

(72) Inventors: Hyeong Woo Kim, Seoul (KR); Yoon Seok Na, Seoul (KR); Yul Joong Kim, Seoul (KR)

(73) Assignee: CJ CHEILJEDANG CORPORATION, Seoul (KR)

() Term: 15 Years

(21) Appl. No.: 29/933,161

(22) Filed: Mar. 18, 2024

(51) LOC (15) Cl. 09-01

(52) U.S. Cl.

USPC D9/643; D9/707

(58) Field of Classification Search

USPC D9/414, 416, 433, 434, 600, 601, 602, D9/606, 618, 643, 652, 658, 661, 669, D9/695-697, 702, 703, 707; D19/69; D20/27

CPC B65D 2203/02; B65D 2203/00; B65D 23/14; B65D 83/38; B65D 1/40; B65D 5/4212; B65D 33/004; B65D 81/34; B65D 2581/34; B65D 81/3461; B65D 2231/001; B65D 81/3888; G09F 2003/0251; G09F 2003/0272; G09F 2003/0273; G09F 2023/0025; G09F 2023/0091

(57) CLAIM

The ornamental design for a bag for food packing, as shown and described.

DESCRIPTION

The file of this patent contains at least one photograph executed in color. Copies of this patent with color photograph(s) will be provided by the Office upon request and payment of the necessary fee.

FIG. 1 is a perspective view of a bag for food packing showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

BIBIGO™ is a registered trademark of CJ CHEILJEDANG CORPORATION forming part of the claimed design.
